DEVICE FOR INDICATING IMPROPER
TRIGGER PULLING

Paul Eidelman, New York, N. Y., assignor of one-half to Nathan P. Zablow, New York, N. Y.

Application August 3, 1940, Serial No. 351,002

3 Claims.

(Cl. 42—1)

The invention relates to a device for indicating when the trigger of a rifle, shotgun, pistol or other trigger-operated firearm has been moved or pulled beyond the point at which the hammer is actuated, that is, the point in the movement of the trigger at which the firing or detonation of the firearm takes place. Trigger-operated firearms are usually so constructed that the trigger is capable of travel beyond the firing point. This fact is availed of in the present invention which provides means for use in teaching the art of properly manipulating the trigger of a firearm.

It is well known that all too frequently the projectile from a firearm properly pointed before firing fails to reach the objective with which it was alined, for example, the bull's eye of a target, because the shooter does not properly operate the trigger. Instead of smoothly squeezing the trigger without hitch or jerk until the trigger reaches the point at which the hammer is actuated to detonate the cartridge, the shooter, especially if a beginner, often jerks the trigger to the firing point and thereby moves the barrel of the firearm out of alinement with the objective. Heretofore, so far as I am aware, there has been no means provided for indicating to the shooter or to his instructor whether the misdirected shot has been caused by poor marksmanship generally, that is to say, by both improper aiming and trigger operation or by improper trigger operation alone.

The object of the present invention is to provide a device by means of which both the shooter and the instructor (if the shooter has one) may know, after a real shot or simply a trigger pull, whether the trigger was properly squeezed or pulled to the firing or hammer actuating point, or whether it was jerked to that point and beyond it.

This object is accomplished by locating in the path of movement of the trigger beyond the firing point a movable member arranged to be moved by the trigger after it has been pulled beyond the firing or hammer-actuating point. If the movable member is moved a sufficient amount by the trigger, the member renders effective other elements of the device to actuate a signal which may be visual or audible, and thereby indicate to the shooter and the instructor that the pulling of the trigger was effected by a jerk which carried the trigger beyond the firing or hammer-actuating point. The device may be entirely mechanical and mounted wholly on the firearm, or it may be electrical, mounted either

wholly on the firearm or partly on the firearm and partly on a support at a distance from the firearm and under the control of the instructor. Because of simplicity of structure and convenience in use the device is preferably electrical, although it will be understood that the invention is not to be restricted to such embodiment. It will be further understood that the device is adapted for use in real shooting practice, or with only trigger pulling or squeezing or simulated shooting.

In the accompanying drawing illustrating the device of the invention as applied to a rifle of usual construction, Fig. 1 is a side elevation of a portion of the rifle in the vicinity of the trigger and showing the support on which the contact pieces are mounted attached to the trigger guard, and Fig. 2 is a longitudinal section through the trigger and guard, and showing the contact support and contact pieces in top plan view, the electric circuit and signal being shown diagrammatically.

The trigger-operated firearm to which the device of the invention is adapted to be applied, 25 may be of any usual construction, the portion of the rifle shown in Fig. 1 comprising a barrel 5 supported in a stock 6, and a butt 7. Extending downwardly from the underside of the firearm from about the point of junction of the stock 6 and butt 7, is a trigger 8 and trigger guard 9. When the trigger has been moved or pulled to substantially the point indicated by the dotted lines 10, the hammer 11 is actuated. This point in the path of movement of the trigger is known as the firing or hammer-actuating point, or the point at which the firing or detonation of the firearm takes place. As is known, the trigger is capable of substantial further movement, although it is common practice to cease pressure on the trigger at the moment the hammer is actuated. Usually, the experienced shooter will stop squeezing the trigger at about the point 10, although some marksmen continue the pressure on the trigger until the trigger reaches the limit of possibility of movement toward the right hand end 12 (viewing Fig. 1) of the trigger guard 9.

A commonly experienced detriment to accurate shooting is an uneven or jerky pressure on the trigger, especially a final quick jerk of the trigger as it reaches the point 10 of firing or hammer actuation. This may happen even though the movement of the trigger as far as the point 10 is smooth and even. This sudden jerk on the trigger in reaching the firing point is liable to result in knocking the firearm out of alinement

with its objective, and is the frequent cause of poor marksmanship. The novice or beginner in the art of shooting often finds it difficult to exert the even pressure on the trigger to move it to the firing point 10 without disturbing the alignment of the firearm with its objective. And even experienced marksmen will occasionally err in this respect without knowing the real reason for the lowering of their scores. The device of the present invention is designed to indicate this error if it occurs in a shooter's performance.

If the movement of the trigger past the firing point 10 is continued to the limit of movement toward the end 12 of the trigger guard, the hammer is first actuated and then the trigger moves through a short space. The device of the present invention is actuated by the trigger as it traverses this space. Accordingly, if the detonation of the firearm is followed immediately without appreciable break in the continuity of sound by the operation of the signal, that indicates that the trigger was jerked past the firing or hammer actuating point 10. If the firearm is detonated without a sounding of the signal that means that the shooter ceased pressure on the trigger at substantially the firing point 10. If the firearm is fired and an appreciable interval afterwards the signal is operated, that means that the shooter squeezed the trigger properly as far as the firing point 10, but followed the trigger through to the limit of its movement. The interpretation of these occurrences assists the teacher in his instructions to the pupil or beginner and assists the experienced shooter in correcting his own faults in trigger squeezing.

The device of the invention shown in the drawing in use in connection with a rifle, which is a typical application of the invention, comprises a flexible contact strip or piece 14 secured at one end to a block of insulating material 15 fixed in one corner of a contact support 16 one end of which is bifurcated to provide resilient arms 17 which are adapted to embrace tightly the end 12 of the trigger guard 9. An expansion coil spring 18 tends to press the contact piece 14 into normal position (as shown) in the path of travel of the trigger 8 when it is moved beyond the firing position 10 to almost the limit of its movement toward the end 12 of the trigger guard. If the pressure on the trigger is strong (the usual finger pressure is sufficient) and it is exerted until the trigger reaches substantially the limit of its movement, the contact piece 14 will be moved against the contact point 20 which is the end of the screw 21 threaded into the support 16. This action closes the circuit consisting of the wires 22 and 23 fed by the battery 24. The bell signal 25 is located in the circuit. The wire 22 is connected with the contact piece 14 and the wire 23 is connected with the contact support 16.

From the foregoing description it will be understood that if the trigger is jerked past the point of firing or hammer actuation 10 and forced against the contact piece 14, pushing it against the contact point 20, the circuit through the wires 22 and 23 will be closed and the signal 25 operated. Since accurate firearm shooting depends largely on acquiring good habits, of which proper trigger squeezing is an important one, the use of the device of the present invention which indicates the results of proper and improper trigger

operation, will tend to form and confirm the habit of correct trigger squeezing.

Having thus described the invention, what I claim as new is:

- 5 1. In firearms of the character described including a hammer, a trigger movable to a firing position at which the hammer is actuated and capable of movement beyond that position, and a trigger guard, a device operative only when 10 the trigger has been moved beyond the firing position at which the hammer is actuated for indicating when the trigger has been pulled beyond such position at which the hammer is actuated, said device comprising a contact support 15 mounted on the trigger guard, a resilient contact piece mounted on the support and insulated therefrom, said resilient contact piece being disposed beyond the path of movement of the trigger between initial and firing positions but disposed in the path of the trigger as the latter is pulled beyond the firing position at which the hammer is actuated, a stationary contact on the support arranged to be touched by the resilient contact when the latter is moved far enough by the trigger, an electric circuit in which the contacts are located and a signal in the circuit arranged to be operated by the closing of the circuit through the contacts.
- 20 2. In firearms of the character described including a hammer and a trigger movable to a firing position at which the hammer is actuated and capable of movement beyond that position, a device operative only when the trigger has been moved beyond the firing position at which the hammer is actuated for indicating when the trigger has been pulled beyond such position at which the hammer is actuated, said device comprising a contact piece movably mounted on the firearm and insulated therefrom, a stationary 25 contact mounted on the firearm, said movable contact being disposed beyond the firing position of the trigger and in the path of movement of the trigger beyond the firing position and arranged to be moved by the trigger against the stationary contact when the trigger has been pulled beyond the firing position at which the hammer is actuated, an electric circuit in which the contacts are located and a signal in the circuit arranged to be operated when the circuit is closed through the contacts.
- 30 3. In firearms of the character described including a hammer and a trigger movable to a firing position at which the hammer is actuated and capable of movement beyond the firing position, a device operative only when the trigger has been moved beyond the firing position at which the hammer is actuated for indicating when the trigger has been moved beyond such position at which the hammer is actuated, said device comprising a signal, and means for actuating the signal when the trigger has been moved beyond the firing position at which the hammer is actuated consisting of a movable member mounted on the firearm and located beyond the 35 firing position of the trigger and in the path of the trigger as it travels beyond the firing position at which the hammer is actuated and means connecting the signal with the movable member when the latter is moved by the trigger for operating the signal.
- 40 4. In firearms of the character described including a hammer and a trigger movable to a firing position at which the hammer is actuated and capable of movement beyond the firing position, a device operative only when the trigger has been moved beyond the firing position at which the hammer is actuated for indicating when the trigger has been moved beyond such position at which the hammer is actuated, said device comprising a signal, and means for actuating the signal when the trigger has been moved beyond the firing position at which the hammer is actuated consisting of a movable member mounted on the firearm and located beyond the 45 firing position of the trigger and in the path of the trigger as it travels beyond the firing position at which the hammer is actuated and means connecting the signal with the movable member when the latter is moved by the trigger for operating the signal.
- 50 5. In firearms of the character described including a hammer and a trigger movable to a firing position at which the hammer is actuated and capable of movement beyond the firing position, a device operative only when the trigger has been moved beyond the firing position at which the hammer is actuated for indicating when the trigger has been moved beyond such position at which the hammer is actuated, said device comprising a signal, and means for actuating the signal when the trigger has been moved beyond the firing position at which the hammer is actuated consisting of a movable member mounted on the firearm and located beyond the 55 firing position of the trigger and in the path of the trigger as it travels beyond the firing position at which the hammer is actuated and means connecting the signal with the movable member when the latter is moved by the trigger for operating the signal.
- 60 6. In firearms of the character described including a hammer and a trigger movable to a firing position at which the hammer is actuated and capable of movement beyond the firing position, a device operative only when the trigger has been moved beyond the firing position at which the hammer is actuated for indicating when the trigger has been moved beyond such position at which the hammer is actuated, said device comprising a signal, and means for actuating the signal when the trigger has been moved beyond the firing position at which the hammer is actuated consisting of a movable member mounted on the firearm and located beyond the 65 firing position of the trigger and in the path of the trigger as it travels beyond the firing position at which the hammer is actuated and means connecting the signal with the movable member when the latter is moved by the trigger for operating the signal.
- 70 7. In firearms of the character described including a hammer and a trigger movable to a firing position at which the hammer is actuated and capable of movement beyond the firing position, a device operative only when the trigger has been moved beyond the firing position at which the hammer is actuated for indicating when the trigger has been moved beyond such position at which the hammer is actuated, said device comprising a signal, and means for actuating the signal when the trigger has been moved beyond the firing position at which the hammer is actuated consisting of a movable member mounted on the firearm and located beyond the 75 firing position of the trigger and in the path of the trigger as it travels beyond the firing position at which the hammer is actuated and means connecting the signal with the movable member when the latter is moved by the trigger for operating the signal.
